UNITED STATES PATENT OFFICE.

WILLIAM W. LASKER, OF BROOKLYN, NEW YORK, ASSIGNOR TO POWERS ACCOUNTING MACHINE COMPANY, OF NEW YORK, N. Y., A CORPORATION OF DELAWARE.

INTERLOCKING RELEASE MECHANISM FOR KEYBOARDS.

1,305,556.

Specification of Letters Patent. Patented June 3, 1919.

Application filed September 28, 1917. Serial No. 193,651.

To all whom it may concern:

Be it known that I, WILLIAM W. LASKER, a citizen of the United States, residing in borough of Brooklyn, in the county of 5 Kings, city and State of New York, have invented certain new and useful Improvements in Interlocking Release Mechanism for Keyboards, of which the following is a specification.

10 This invention relates to interlocking mechanism adapted for use with card perforating machines, typewriting machines, and the like for preventing the actuation of more than one key at a time, and the invention 15 also relates to means for at will releasing and rendering said mechanism inoperative.

While my invention is not limited in its application to card perforating machines, it 20 is herein illustrated and described in connection with such a machine such as is described in my copending applications, Serial No. 116,597, filed August 26th, 1916, and Serial No. 159,054, filed April 2nd, 1917.

25 Herein, I describe minute details of the invention, but it is noted that the invention is not limited to these details, since the details of construction and combination may be greatly varied without departing from the 30 scope of my invention as claimed.

In the accompanying drawing showing by way of example one of many possible embodiments of the invention,

35 Figure 1 is a perspective view showing a part of a card perforating machine provided with my invention;

Fig. 2 is a transverse vertical sectional view, showing in elevation certain details of my invention in one position;

40 Fig. 3 is an elevation partly in section showing said details in another position, and

Fig. 4 is a fragmental side elevation showing the releasing means for releasing the interlocking mechanism.

45 In my above mentioned copending applications there is shown a machine provided with a carriage, a keyboard, a punch setting mechanism operatively connected to the keyboard, an escapement for the punch carriage, and means for controlling the movements of 50 the punches and carriage, and the rails on which said carriage moves.

In the present specification, description

and illustration of the main-frame of the perforating machine are omitted.

55 My interlocking mechanism and releasing means are shown herein in connection with a carriage 10, similar to the one described in said applications, comprising side-plates 11, and a supporting frame 12 provided with 60 flanged wheels 14 for supporting the same on suitable track rails such as shown in said applications. Upon the upper parts of said side-plates 11, is mounted, a fixed comb plate 15, upon which is mounted a recessed block 65 16, in the recesses of which are disposed plunger pins 18 (Fig. 4), held in place by means of cover plate 19, suitably secured to the top of the recessed plate.

70 Transversely mounted between the plates 11, is a crank-shaft 21, on which are mounted a plurality of bell-cranks 22, all but three of which are omitted for purposes of clearer illustration. The upper arms 24 of the bell-cranks are received between the teeth of the 75 comb plate 15, and are adapted to be engaged and moved by the plunger pins 18, which plunger pins are actuated by flexible pushed cables, not shown herein, illustrated and described in said copending applications.

80 Certain of the lower arms 25 of said bell-cranks have pivoted thereto punch operating rods 26, adapted to operate punch pins not shown herein, said lower arms and operating rods are held in normal upper position 85 by means of suitable springs 28. One of said lower arms 30 is connected by means of a slot and pin connection 31, 32, to means for controlling the escapement wheel 35 carried on the stub shaft 36 (Fig. 2). The escapement mechanism and co-operating parts 90 form no part of the present invention, and therefore description thereof is omitted herein.

95 The side plates 11 are provided with vertical slots 38 in which are vertically slidable the reduced end portions 39 of the movable comb plate 40, between the teeth of which are received the said lower arms 25 and 30 of the bell-cranks. The said reduced end 100 portions are provided with recesses 42 in which engage the ends of rock levers 43 carried upon a rock shaft 45, mounted in the said plates 11, said rock levers 43 and, consequently, the comb plate 40 are held at the 105 upward limit of movement, by means of

springs 46 strained between said rock levers and the upper part of said plates 11. Pivoted upon screws 48, carried on the upper part of the comb plate 40, are locking levers 5 49, each formed with a reduced intermediate portion 50, normally disposed between said lower arms of the bell-crank. The lower ends of said locking levers are formed into enlarged heads forming inclined shoulders 10 52 normally disposed beneath said lower arms and adapted to be contacted and pushed aside by the first of said lower arms which is depressed, whereby the lower arm 15 assumes a position between said enlarged heads (Fig. 3) thereby positively holding said locking levers out of their normal position and in the laterally inclined position shown in Fig. 3. When the locking levers are in the position shown in Fig. 3 any de- 20 pressing of any other lower arm of said bell-crank causes such arm to be engaged and stopped by the inclined shoulder 52 adjacent thereto, thereby preventing the further depression of such arm and the operation of 25 the punch mechanism or other mechanism operated thereby.

Sometimes, however, it is desired to render inoperative the interlocking mechanism just described, and a description of the means for 30 accomplishing this will now be given.

Upon the stub shaft 36 (Fig. 2), there is mounted a fixed collar 60, held in place by means of a set screw 61, a movable collar 62, and a loosely mounted handle 64, said handle 35 being held in place by means of a washer 65, secured by means of an end screw 66, screwed in the end of the stub shaft. Upon the collars 60, and 62, are provided respectively a fixed radial pin 68 and a movable 40 radial pin 69, between which engages an inwardly projecting pin 70 carried by the handle 64. Upon the movable collar 62 there is fixed a lever arm 72 (Fig. 4), connected by means of a link 73 to one of the rock 45 arms 43.

It will be seen that when the handle 64 is moved in the direction of the arrow of Fig. 1, the inwardly projecting pin 70 engages the movable pin 69, causing the lever arm 72 to move in the direction of the arrow of 50 Fig. 4, thereby causing the depression of the link 73 the rock arms 43 and the comb plate 40, and the lowering of the locking levers 49 to the position shown by the dotted lines of 55 Fig. 2. This movement causes the inclined shoulders 52 to be moved to assume a position lower than the lower limit of movement of the lower arms of the bell-crank, thereby preventing any lateral movement of any of 60 the locking levers 49, by the lower arms when any of said lower arms is depressed.

Movement of the handle 64 in a direction opposite to the direction of the arrow of Fig. 1, causes the pin 70 to engage the fixed 65 pin 68, whereby movement may be communi-

cated to the punch carriage as a whole, to move the same back against the tension of its operating spring, not shown herein.

The operation of the mechanism may be briefly summarized as follows:

Any depression of any lower arm of any bell-crank forces aside the adjacent locking levers and causes the inclined shoulders 52 of the locking levers to dispose themselves under the remaining lower arms, thereby preventing any depression of said remaining lower arms. When the depressed arm is raised the locking levers assume by gravity their normal position, as shown in Fig. 2. When it is desired to release the interlocking 75 mechanism or to render it inoperative, the handle 64 is moved in the direction of the arrow of Fig. 1 thereby lowering the locking levers 49 to the inoperative position shown in dotted lines in Fig. 2. 80

I claim as my invention:

1. In an interlocking release mechanism, the combination of a plurality of operating parts; devices associated with the parts for preventing the operation of more than one 90 part at a time; and means for rendering said devices inoperative.

2. In an interlocking mechanism, the combination of a plurality of lever arms; a movable member disposed across said arms; and locking levers pivoted to said member and disposed between the arms and having inclined shoulders at their free ends.

3. In an interlocking release mechanism, the combination of a plurality of lever 100 arms; a movable member disposed across said arms; locking levers pivoted to said member and disposed between the arms and having inclined shoulders at their free ends; and means for moving said member toward 105 or away from the arms.

4. In an interlocking release mechanism, the combination of a frame; a vertically movable comb plate mounted therein; movable arms disposed between the teeth of the 110 comb plate; and locking levers pivoted to the upper part of the comb plate and having reduced intermediate portions disposed between said arms, and inclined shoulders disposed beneath the arms.

5. In an interlocking release mechanism, the combination of a frame; a vertically movable comb plate mounted therein; movable arms disposed between the teeth of the comb plate; locking levers pivoted to the 120 upper part of the comb plate and having reduced intermediate portions disposed between said arms, and inclined shoulders disposed beneath the arms; and means for lowering the comb plate.

6. In an interlocking release mechanism, the combination of a frame; a vertically movable comb plate mounted therein; movable arms disposed between the teeth of the comb plate; locking levers pivoted to the 125

upper part of the comb plate and having reduced intermediate portions disposed between said arms and inclined shoulders disposed beneath the arms; means normally 5 yieldably holding the comb plate in uppermost position; and means for depressing the comb plate.

7. In an interlocking release mechanism, the combination of a frame; a vertically 10 movable comb plate mounted therein; movable arms disposed between the teeth of the comb plate; locking levers pivoted to the upper part of the comb plate and having reduced intermediate portions disposed between 15 said arms, and inclined shoulders disposed beneath the arms; a rocking handle; and an operative connection between the handle and the comb plate.

8. In an interlocking release mechanism, 20 the combination of a carriage frame provided with vertical side slots; a vertically disposed comb plate having its ends projecting through said slots; a crank shaft mounted in said frame; punch operating 25 cranks mounted on said shaft and comprising upper arms, and lower arms disposed between the teeth of said comb plate; a plunger block on said frame; plunger pins in said block and adapted to engage and 30 move said upper arms; locking levers pivoted to the upper part of said comb plate and having intermediate portions disposed between said lower arms, and inclined shoulders disposed beneath said lower arms; 35 a rock shaft on said frame; rock levers thereon engaging the ends of the comb plate; a stub-shaft; a handle loosely mounted thereon; a collar on the stub-shaft adapted to be moved by said handle; and a con-

nexion between the collar and one of the 40 rock levers.

9. In an interlocking release mechanism, the combination of a carriage frame comprising side plates, each provided with a vertical slot; a movable comb plate having 45 slotted reduced ends vertically movable in said vertical slots; a crank shaft mounted in said side plates; bell cranks mounted on said shaft and having upper arms received between the teeth of the fixed comb plate 50 and lower arms received between the teeth of the movable comb plate; a recessed block on said fixed comb plate; plunger pins in the recesses of said block and adapted to engage and move said upper arms; locking 55 levers pivoted to the upper part of said movable comb-plate and having reduced intermediate portions disposed between said lower arms and inclined shoulders disposed beneath said lower arms; punch operating 60 rods pivotally carried on the free ends of said lower arms; a rock-shaft passed through said side plates; rock-levers fixed on said shaft and engaging in the recesses of said reduced ends; a stub-shaft mounted 65 on said carriage frame; a fixed collar fixed on said stub-shaft and provided with a radial pin; a movable collar on said stub-shaft provided with a radial pin and a lever arm; a link between said lever arm and said rock 70 lever; and a handle loosely mounted on said stub-shaft and provided with a laterally projecting pin disposed between said radial pins.

WILLIAM W. LASKER.
